UNITED STATES PATENT OFFICE.

LEVI M. BOWMAN, OF TULSA, OKLAHOMA, ASSIGNOR OF ONE-HALF TO WILLIAM A. SMITH, OF TULSA, OKLAHOMA.

HYDROCARBON-BURNER.

1,272,201.

Specification of Letters Patent.

Patented July 9, 1918.

Application filed May 16, 1917. Serial No. 168,993.

To all whom it may concern:

Be it known that I, LEVI M. BOWMAN, a citizen of the United States, residing at Tulsa, in the county of Tulsa, and State 5 of Oklahoma, have invented certain new and useful Improvements in Hydrocarbon-Burners, and I do hereby declare the following to be a full, clear, and exact description of the invention, such as will enable 10 others skilled in the art to which it appertains to make and use the same.

This invention relates to improvements in hydrocarbon burners.

The object of the present invention is to 15 improve the construction of hydrocarbon burners and to provide a simple, practical and inexpensive hydrocarbon burner of strong and durable construction which will be adapted for burning kerosene and to 20 crack or break up the kerosene into a gas.

A further object of the invention is to 25 provide a hydrocarbon burner of this character equipped with a cracking chamber adapted to be heated by heat radiated from the combustion chamber and maintained at a temperature adapted to produce a flame which will remain approximately at the same height, after the burner has been operated for a considerable period of time, as 30 when first started so that the continued operation of the burner will not produce too excessive heat in the presence of the kerosene passing through the cracking chamber as to consume all visible flame in the combustion chamber passage.

Another object of the invention is to provide a hydrocarbon burner which will not readily burn out and in which the parts will be arranged to produce a blue flame 40 and afford an easy escape of the same to the exterior and at the same time maintain the combustion chamber free from soot and accumulation.

With these and other objects in view, the 45 invention consists in the construction and novel combination of parts hereinafter fully described, illustrated in the accompanying drawing and pointed out in the claims here-to appended; it being understood that various changes in the form, proportion, size and minor details of construction, within

the scope of the claims, may be resorted to without departing from the spirit or sacrificing any of the advantages of the invention.

55

In the drawing:

Figure 1 is a vertical sectional view of a hydrocarbon burner constructed in accordance with this invention.

Fig. 2 is a plan view of the deflecting 60 plate.

Like numerals of reference designate corresponding parts in all the figures of the drawing:

In the accompanying drawing, in which 65 is illustrated the preferred embodiment of the invention, the hydrocarbon burner comprises in its construction an annular horizontally disposed member 1 preferably consisting of a casting and provided with a 70 central opening 2 and having an interior annular chamber 3 surrounding the central opening and adapted to form a cracking chamber. The annular member, which is supported by a substantially cylindrical shell or casing 4, is provided with an inlet opening 5 threaded to receive the threaded end 6 of a nipple 7, which is adapted to be connected with any suitable source of supply. The casing or shell 4, which receives 60 within its upper portion the annular member 1, is secured to the same by means of screws 8, or other suitable fastening devices, and it is of cylindrical form to conform 75 to the configuration of the annular member 1.

The annular member 1 is provided at its upper face with a recess or concavity 9, and the upper edges of the annular member 1 fit in a lower peripheral recess 10 of a top 90 plate 11 forming a deflecting plate for the hydrocarbon burner and removably fitted on the said annular member 1. The top or plate 11 extends above the shell or casing 4, and the annular recess forms a shoulder 95 or seat to rest upon the upper edges of the annular member and at the same time provides a reduced portion to extend into the concavity or recess 9 so as to interlock the top or plate 11 with the annular member 100 and thereby prevent accidental displacement of the former. The deflecting plate

11 is spaced from the bottom of the recess or concavity 9 of the annular member 1 to provide a combustion chamber and the top or plate 11 is provided with an imperforate central portion and it has upwardly tapered openings 12 surrounding the solid or imperforate central portion and located at the outer portion of the combustion chamber beyond the central opening 2, the imperforate area or solid portion of the top or plate 11 being greater than the opening 2 and extending beyond the same so that the gas from the burner will be projected through the opening 2 against the imperforate portion of the deflecting plate 11, producing a thorough mixing of the gas and air and providing a mixture which is adapted to burn with a blue flame which, owing to the curvature of the bottom of the recess or concavity 9, finds an easy passage to the outlet openings 12, and a blue flame is produced which burns from the central opening 2 to the outlet openings. This tends to keep the combustion chamber free from soot and accumulation. The cracking chamber 3, which receives the kerosene and breaks the same up into a gas, is heated by the heat radiated from the combustion chamber and the gas passes downward through an approximately L-shaped pipe 13 having an upwardly extending vertical arm and an inwardly extending horizontal arm, the vertical arm being threaded at 14 into the bottom of the cracking chamber and the horizontal arm being provided with a threaded terminal 15 which is connected with a needle valve casing 16 having a threaded opening at one side to receive the horizontal arm of the pipe 13. The needle valve casing, which preferably consists of a casting, is equipped with a packing nut 17, and the valve proper 18 consists of a rod reduced at the upper portion to form a shoulder 19 and to provide a pin or extension 20. The extension or needle 20 passes through a jet opening 21 of the needle valve casing and is adapted to maintain the same in a clean condition by removing the foreign matter, such as amorphous wax, etc., from the said opening. This removal of the wax and cleaning of the jet opening is effected by an adjustment of the needle valve. No claim is made in the present application to such construction, as it forms the subject-matter of an application filed by me March 10, 1917, Serial No. 153,893, Patent No. 1,241,334, Sept. 25, 1917. The needle valve is connected by a suitable pivot 22 with an operating lever 23 fulcrumed at its rear end at 24 and having its front portion extending through a slot 25 of the shell or casing and adapted to be readily grasped by the operator to adjust the needle valve. The kerosene entering the cracking chamber

breaks up into gas and passes out from the cracking chamber through the pipe 13 to the needle valve and it escapes through the needle valve casing at the jet opening in the form of a jet which impinges against the under side of the deflecting plate 11, breaking and extending and spreading outward into the combustion chamber and passing out through the outlet openings 12. The upward curve of the marginal portion of the recess or concavity 9 allows an easy passage of the flame from the combustion chamber to the openings 12. The size of the annular member not only increases the life and durability of the same by preventing the annular member from burning out but it also insures a longer passage of the gases from the inlet opening 2 of the combustion chamber to the outlet openings 12. The flame in passing out of the burner will remain at the same or approximately the same height any number of hours after the generation of gas in the collecting chamber and it does not vary after the burner has been in operation for some time, as there is no liability of the cracking chamber becoming excessively heated owing to the placing of the combustion chamber over the cracking chamber. This has been found by experience and the device is also rendered easily and cheaply manufactured owing to the simplification of the construction.

The hydrocarbon burner is preferably equipped with a supplemental or auxiliary cap 26 supported above in spaced relation with the deflecting plate 11 by a depending annular flange 27 which fits in a peripheral recess 28 of the deflecting plate. The superimposed cap is provided with holes 29, and the purpose of the cap is to allow the escaping flame to reach a higher elevation and have a more uniform blue color.

What is claimed is:

1. A hydrocarbon burner including an outer casing, a gas generating member removably secured to same, said gas generating member having a central opening therethrough and an interior chamber surrounding the same, said gas generating member having a concave recess in its upper surface, said chamber being provided with inlet and outlet openings, a deflecting plate supported by and above the gas generating member, said deflecting plate having a peripheral recess in its upper surface, and a cap supported in spaced relation to the deflecting plate.

2. A hydro-carbon burner including an outer casing, a gas generating member removably secured to same, said gas generating member having a central opening therethrough and an interior chamber surrounding the same, said gas generating member having a concave recess in its upper

per surface, said chamber being provided with inlet and outlet openings, a deflecting plate, said deflecting plate being provided with a lower peripheral recess, said lower recess engaging the upper edge of the gas generating member, said deflecting plate being provided with an upper peripheral recess, and a cap supported in the upper re-

cess in spaced relation to the deflecting plate. 10

In testimony whereof I affix my signature in presence of two witnesses.

LEVI M. BOWMAN.
